M. CLARK.

AIR MOTOR.

APPLICATION FILED DEC. 8, 1916.

1,265,747.

Patented May 14, 1918.

UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

AIR-MOTOR.

1,265,747.

Specification of Letters Patent. Patented May 14, 1918.

Application filed December 8, 1916. Serial No. 135,753.

To all whom it may concern:

Be it known that I, MELVILLE CLARK, a citizen of the United States, residing at Chicago, in the county of Cook and State 5 of Illinois, have invented new and useful Improvements in Air-Motors, of which the following is a specification, reference being had to the accompanying drawings, forming a part thereof.

10 The purpose of this invention is to provide an improved air motor, particularly adapted for operating the note-sheet feeding devices of an automatic piano player. It consists in the elements and features of 15 construction shown and described, as indicated in the claims.

In the drawings:

Figure 1 is a perspective view from the forward side of an air motor embodying 20 this invention, the same being shown in connection with adjacent parts of the piano player action which it serves.

Fig. 2 is a fore-and-aft vertical section at the line, 2—2, on Fig. 1, through one of 25 the motor pneumatics and its valve chamber.

Fig. 3 is a section similar to Fig. 2 of a modified form.

Fig. 4 is a horizontal section of the tempo 30 valve chamber, taken above the valve therein.

Fig. 5 is a section at the line, 5—5, on Fig. 4.

Fig. 6 is an axial section of a fly wheel 35 and spring-connected crank arms by which the fly wheel is connected with the shaft on which it is mounted.

The air motor illustrated in the drawings comprises a plurality,—as illustrated, five,—motor pneumatics, 1, having their back or base-boards, 1^a, fixed, and having their moving walls, 1^b, all oscillating in the same direction from said fixed walls. Journalized in 40 bearings, 3—3, fixed with respect to said fixed wall or back, there is a crank shaft, 4, having five cranks, 4^a, corresponding to the five pneumatics, and connected by a pitman, 6, with the moving walls, 1^b, respectively, of said motor pneumatics. In the form shown 45 in Figs. 1 and 2, the valve chamber for controlling the motor pneumatic is mounted upon the fixed board or back, 1^a, which is at the forward side of the motor, and is mounted for service in the position shown

in Fig. 1. At said forward side of the back or fixed members of the motor pneumatic, there is mounted protruding therefrom as a 55 transverse rib thereon, a chamber which is partitioned so as to form an exhaust air chamber, 7, which extends across all the pneumatics, and individual valve chambers, 8, one for each pneumatic,—the valve chambers each having a port, 9, leading into the exhaust air chamber, 7, and a port, 10, opening to the atmosphere. In the valve chamber between the two ports, there are two valves, 11 and 12, mounted on a common 60 stem, and on that stem thrust apart by the reaction of the spring, 13, forcing each valve to its proper seat, controlling respectively the ports, 9 and 10. The valve stems extend out through the atmosphere port, and are 65 operatively connected with a lever, 14, which is fulcrumed at one end on the back board or fixed wall of the motor pneumatic, the other end of the lever being connected by a link, 15, with the pitman, 6, pertaining to 70 the same motor pneumatic. For such connection, in order to give the valve its proper 75 action, the pitman is extended from its bearing on the crank wrist in a direction at an angle to the extent of the pitman from the 80 crank wrist to its connection with the moving wall of the motor pneumatic, the relative arrangement of the parts and pivotal connections being such as to cause the valve of each pneumatic to be open for communication with the exhaust and with the atmosphere in proper time with respect to the 85 position of the crank to cause the collapse of the motor pneumatic to occur when the crank is in the position for receiving the impulse of the motor pneumatic to the best 90 advantage for the purpose of rotating the shaft, the spring connection between the two valves causing the seating periods to overlap, preventing waste of air.

In the form shown in Figs. 3 and 4, the moving walls of the motor pneumatics are at opposite sides of the fixed wall from the other form, the valve chambers and the exhaust air chamber being also at the opposite 100 side below the pivoted end of the moving wall, and the pitmen for operating the valves are connected directly to the valve stems, which extend upward,—the atmos-

- phere opening being at the upper side of the valve chambers,—and at their upper ends are connected to the forward ends of the pitmen which are extended forward of their connection with the moving walls of the motor pneumatics for that purpose. The resultant timing of the action of the valves with respect to the position is substantially the same as in the other form.
- 10 In the use of air motors for the purpose of operating the note-sheet propelling devices of an automatic player, it has been observed that notwithstanding apparently perfect uniformity in the construction, different 15 motors yield different speed for the same partial vacuum and the same adjustment of the speed-governing valves or other devices. I have found that this variation is in part due to the fact that the rubber tubes generally used for connecting the motor with the exhaust devices, or sources of exhaust tension, being of varying rigidity and varying flexibility are collapsed more or less by the same degree of exhaust tension, the collapse, of course, restricting the air passage through them, and this restriction, therefore, being different in different motors; and when, as is intended to be the fact in previous 25 constructions, the aperture at which the rubber tube is connected with the air motor or with the chamber of the tempo-regulating valve is equal to the maximum cross-sectional area of the rubber tube, the variation in the collapse of the rubber tubes in different instances causes a variation 30 in the exhaust action which is subject to the regulation of the valve, and so causes the same adjustment of that valve to yield different results in respect to the speed of 35 the motor. To overcome this difficulty, therefore, I provide at the connection of the tube, 20, which leads from the exhaust devices, (not shown), to the tempo-regulating valve chamber, 21, a choke device consisting 40 of a slide member, 22, mounted for sliding across the port and choking it, said slide member being connected for such sliding adjustment with a screw, 24, which is externally-accessible, so that the mechanic in assembling and testing the devices can adjust 45 the choke to reduce the port to the capacity of the particular flexible rubber tube which is connected, in accordance with the degree to which that rubber tube is collapsed by 50 the exhaust tension.
- From a variety of causes such as the varying stiffness of the flexible sides of the motor pneumatics, and other unavoidable variations in the parts affecting the ease with 55 which they operate, it is found that even when the exhaust tension reaching the tempo-regulating valve chamber is the same, the same speed of the motor does not always result from the adjustment of the tempo-regulating valve at the same position. The usual form, and according to experience the most desirable form, of the tempo-regulating valve port and valve is that shown in the drawings in which the valve chamber, 25, is partitioned by a valve seat, 26, which has a 70 longitudinally-extending port 26^a, tapered in width from end to end, the valve, 27, being arranged for sliding over that port longitudinally. Whether the port is of the tapered form or not, it is covered and uncovered by the valve by movement of the latter longitudinally with respect to the port. To overcome the defect above mentioned consisting of the variation in the speed of the motor for the same adjustment of the valve, I provide means for choking the port, 26^a, through the valve seat by an adjustment of one of its longitudinal edges or walls,—that is, by varying the width of the port or its dimension in the direction transverse to that of the movement of the valve for opening and closing it. This is most conveniently accomplished by pivoting at the apex of the angle formed by the two converging sides of the port, a choke lip 30, 90 which is let into the valve seat, so as to be flush therewith at the upper side and to form the seat of the valve at one longitudinal edge of the port, and providing a spring 31, which acts upon this lip to throw it normally 95 to the position which will allow the port its maximum width, and setting a screw, 32, in from the outside through the valve seat so as to impinge against the back edge of this pivoted lip for forcing it inward to cause it 100 to restrict or narrow up the port transversely to the direction of the movement of the valve. When this choke device is provided, the mechanic in assembling and testing each 105 particular motor, will operate the screw from the outside to adjust the choke device to cause the motor to have a certain pre-determined speed for a certain adjustment of the valve, and in this manner all motors of a given construction can be made to have 110 substantially the same speed with only negligible differences when they have the same valve adjustment. It is desirable that the mechanic shall be advised as to the position of the choke, and for that purpose the pivot, 115 30^a, of the choke lip is made rigid with it and extends out through the top of the chamber, and has connected with it an index finger, 35, which plays over a graduated 120 scale, 37, whose graduations indicate the degree to which the valve port is choked by the lip at any time.
- So far as I am aware, it has not heretofore been regarded practicable to provide an air motor which is employed for operating 125 an automatic player with a fly wheel upon the crank shaft, because while operating to give desirable steadiness to the action of the motor, it tends to prevent quick response in respect to changes of speed to the speed- 130

controlling valve or tempo valve, tending therefore, to cause gradual acceleration and diminution of speed instead of the instantaneous or nearly instantaneous change which is sometimes desirable. I have found it practicable, however, to employ a fly wheel on the crank shaft of this motor by properly relating the weight of the fly wheel to the power of the motor. And I have found that practically all the disadvantage which might result from the presence of a fly-wheel for the reason above suggested, may be obviated by the construction shown and which will now be described in which the fly wheel is connected to the crank shaft yieldingly as to relative rotation of the two. The fly wheel, 40 is mounted loosely on the crank shaft, 4, and on opposite sides of it there are mounted loosely collars, 41 and 42, each of which is connected to the shaft 4, by a coiled spring, said springs, 43 and 44, being coiled in opposite directions. Each of said collars has a radial arm, said radial arms, 41^a and 42^a, being provided at their extremities with abutments, 41^b and 42^b, facing the rim of the fly wheel which is provided on its opposite sides with coöperating abutments, 40^a and 40^b, respectively. Stop collars, 45, 45, fast on the shaft outside the collars, 41 and 42, retain the parts in proper relation on the shaft. The springs, 43 and 44, are normally coiled so that the abutments, 41^b and 42^b, stand adjacent to oppositely-facing sides of the two abutments, 40^a and 40^b, on the fly wheel. When the shaft, 4, starts or is accelerated, the movement or acceleration will not be communicated to the fly wheel until the spring, 43, has been somewhat coiled, the abutment 42^b, being carried away from the abutment, 40^b, during so much of the rotation of the shaft as occurs before the fly wheel starts and acquires the full rotary speed of the shaft. Similarly, when the action of the motor shaft ceases or is retarded, the fly wheel will not stop or suffer like retardment until the spring, 44, has been somewhat coiled, while the abutment, 40^a, on the fly wheel runs away from the abutment, 41^b, on the arm, 41^a, of the collar, 41. The time necessary for the springs to transmit to the fly wheel the motion, acceleration or retardment to the starting acceleration or retardment of the shaft, 4, measures the gain in respect to promptness of response of the motor to the tempo valve which is effected by the yielding connection of the fly wheel to the shaft.

I claim:—

1. In an air motor, in combination with motor pneumatics and the valves which control them; an exhaust air chamber whose communication with the motor pneumatics is controlled by said valves; a flexible and compressible air trunk leading from said air chamber for communication with exhaust

devices, and a choke device at the entrance to said chamber from said air trunk, and means for adjusting said choke device and for securing it as adjusted to regulate the opening into said air chamber according to the capacity of the air trunk as limited by its collapse when connected with the exhaust devices. 70

2. In combination with an air motor and an exhaust air trunk for operating it; a valve chamber interposed between the air trunk and the motor, through which chamber the air from the motor passes to the air trunk, said chamber comprising a valve seat having an elongated port and a valve sliding over said port to close it more or less for regulating the speed of the motor; a choke device in said port independent of the valve, and exteriorly-accessible means for adjusting said choke device to contract or expand the port, said choke device being movable for changing the dimension of the port in a direction transverse to the opening and closing movement of the valve. 80

3. In combination with an air motor and an exhaust air trunk for operating it; a valve chamber interposed between the air trunk and the motor comprising a valve seat having an elongated port; a valve sliding along the length of said port for opening or closing it more or less to govern the speed of the motor, and a choke device in said port movable for contracting and expanding the port in a direction crosswise of the movement of the valve for opening and closing 100 the same. 90

4. In combination with an air motor and an air trunk by which the same is operated; a valve chamber interposed between the air trunk and the motor comprising a valve seat having an elongated tapering port, one of the side walls of said port constituting a choke device pivoted to the valve seat at the apex of the angle formed by the converging sides of said tapering port; a screw extending out through the valve seat and exteriorly-accessible for adjusting said pivoted side of the port, and a valve in the chamber mounted for sliding longitudinally over the port for opening and closing it. 110

5. In an air motor for actuating a player note sheet mechanism, in combination with motor pneumatics, and a crank shaft which they actuate, a fly wheel mounted loose on the crank shaft for rotation there-about, and springs which connect the fly wheel with the crank shaft, adapted to be put under tension by the relative rotation of the crank shaft and fly wheel in either direction from the normal position of the wheel on the 120 crank shaft at which it is held by said springs. 115

6. In an air motor, in combination with motor pneumatics and a crank shaft which they actuate; a fly wheel loose on the crank 130

shaft; collars loose on the shaft at opposite sides of the fly wheel; abutments on the opposite sides of the fly wheel and on the collars respectively, positioned respectively for engagement by rotation of the fly wheel in opposite directions, and springs connecting said collars respectively with the shaft for

reaction in opposite directions around the shaft.

In testimony whereof I have hereunto set my hand at Chicago, Illinois, this 4th day of December, 1916.

MELVILLE CLARK.
